SANITARY DEVICE

Robert E. Sadtler, Cincinnati, Ohio

Application April 26, 1937, Serial No. 139,017

2 Claims. (Cl. 91—18)

This invention relates to dispensing devices for sanitary articles and has special reference to dispensing means for dispensing wet sanitary pads or sheets.

One important object of the invention is to provide a novel general construction of a device for the purpose set forth which can be inexpensively constructed, is simple in construction and without moving mechanism and is indestructible from ordinary use.

A second important object of the invention is to provide a novel device of this kind for holding a pile of pads of absorbent material and moistening the lowermost pad automatically so that when the moist bottom pad is withdrawn for use the pad next above is automatically moistened.

A third important object of the invention is to provide a simple device wherein, by a novel construction, the bottom pad of a pile of flat pads of absorbent material will be wet by capillary attraction from one edge across the whole pad.

With the above and other objects in view, the invention consists in general of certain novel details of construction and combinations of parts hereinafter fully described, illustrated in the accompanying drawing and particularly claimed.

In the accompanying drawing like characters of reference indicate like parts in the several views, and:

Figure 1 is a front elevation of the invention. Figure 2 is a section on the line 2—2 of Fig. 1. Figure 3 is a section on the line 3—3 of Fig. 2. In the embodiment of the invention as shown in the present drawing there is provided a vertically elongated casing made of metal or other suitable material, having a front wall 10, rear wall 12 and side walls 11. In the front wall 10 there is a delivery opening 13 of general inverted V-shape, this opening having a straight bottom edge 14 extending between the side walls 11 from one wall to the other. Extending rearwardly from the front wall level with the edge 14 is a tank top 15 which terminates in spaced relation to the rear wall 12. The rear part of this tank top 15 is downwardly arched to form a transverse trough 16 extending from side wall to side wall. From the rear edge of the trough 16 a partition 17 extends upwardly so that it is spaced from the rear wall 12. This partition extends from side wall to side wall of the casing and thus forms an upstanding tank leg. A casing top 18 is removably fitted on the casing to hermetically close the top of the tank leg when in position. The casing is provided with a bottom

19 which not only forms the casing bottom but also constitutes the tank bottom. Just below the level of the top of the trough 16 the partition 17 is provided with a small feed opening 20 which communicates with the trough.

The pads or pledges consist of an envelope 21 of transparent water proof material such as the commercial product known as "glassine", each envelope being open at its rear edge. Each envelope is filled with water-soluble absorbent material 22, such as cellucotton or the like and this filling 22 projects out of the envelope 21 slightly. These pads are of proper size to fit the casing in front of the partition 17 and lie flat on the tank top 15 with the projecting part of the cotton of the pad resting against the partition 17. These pads are piled one on the other in the casing and, when thus arranged, the cotton of the bottom pad rests in the trough 16.

The metal top 18 is a sufficient barometric seal when the cover 18 is in place. The edge portions of the upstanding water leg extend up a sufficient distance so that when the cover 18 is placed in position it actually contacts the entire perimeter of the water leg opening. If desired, an auxiliary sealing means, such as a water-proofed plug, may be inserted in the upper end of the upstanding water leg after the tank has been filled.

In use, the casing is filled with pads or pledges and the tank filled with water, antiseptic solution or other suitable liquid, the top 18 being immediately closed. A certain amount of the liquid will run into the trough and when it rises above the opening 20 it will stop flowing. The absorbent material of the bottom pad will rest, at its projecting edge, in the liquid in the trough and the liquid will be absorbed through the whole mass of absorbent material in this bottom pad by capillary attraction. The bottom pad may now be drawn out through the opening 13 whereupon the pile of pads will drop and the next pad will be moistened.

When the level of the fluid falls below the opening 20 a bubble of air enters the tank and a little additional fluid flows out into the trough so that the latter is always kept filled to the proper height to effectually wet the bottom pad.

It is to be noted that these pads afford means for thoroughly and sanitarily cleansing the body of the user.

There has thus been provided a simple and efficient device of the kind described and for the purpose specified.

It is obvious that changes may be made in the

form, construction and proportions of the invention without departing from the material principles involved. It is not therefore desired to confine the invention to the exact form herein shown and described but it is desired to include all such as come within the scope of the appended claims.

Having described my invention what I claim as new and desire to protect by Letters Patent is:

- 10 1. In a dispensing device, a casing having a front wall provided with a withdrawal opening, a tank in said casing having a lower body portion provided with a top forming a pad support, said top being level with the bottom edge of said opening, said tank having a rear upstanding leg and having a transverse trough in front of said leg and communicating with the leg through a

small flow opening, and a closure for said leg closing the upper end of the same hermetically.

2. The combination with a casing having a stationary bottom for supporting a stack of absorbent pads, said bottom having a recess therein for receiving fluid for absorption by the lowermost pad of a stack of pads supported on said bottom, said recess having an opening in its wall above its bottom for permitting fluid flow to said recess, said casing having an opening aligned with said bottom whereby a pad supported on said bottom may be removed laterally, and a fluid supply reservoir, sealed against barometric pressure and discharging into said recess through said opening.

ROBERT E. SADTLER.
